CLAIM

(51) **LOC (9) Cl.** 29-02

The ornamental design for a nose protector, as shown and described.

(52) **U.S. Cl.** **D29/108**

DESCRIPTION

(58) **Field of Classification Search** D29/102-112,

FIG. 1 is a perspective view of a nose protector showing our new design;

D29/122; 2/410-414, 416, 422-425, 9-10,

FIG. 2 is a front elevational view thereof;

2/206, 427, 429, 174, 207, 209; D24/110.1-110.4,

FIG. 3 is a side elevational view thereof, the opposite side being a mirror image;

D24/191, 173, 135, 189; 128/857-858, 206.28,

FIG. 4 is a rear elevational view thereof;

128/207.11, 207.17, 201.23, 201.24, 201.25;

FIG. 5 is a top plan view thereof; and,

D16/309; 602/6; 351/155; 606/204.45

FIG. 6 is a bottom plan view thereof.

See application file for complete search history.

The features shown in broken lines in FIG. 1 are shown for illustrative purpose only and form no part of the claimed design.
